UNITED STATES PATENT OFFICE.

MICHAEL P. WEIMAR, OF PHILADELPHIA, PENNSYLVANIA.

BARREL-WASHING MACHINE.

Application filed April 2, 1921. Serial No. 457,874.

To all whom it may concern:

Be it known that I, MICHAEL P. WEIMAR, a citizen of the United States, residing at Philadelphia, county of Philadelphia, State 5 of Pennsylvania, have invented a new and useful Barrel-Washing Machine, of which the following is a specification.

My present invention relates to a barrel washing machine and comprehends novel 10 means for raising the barrel into position to be clamped, novel clamping mechanism, novel means for revolving the barrel and a novel construction and arrangement of brushes whereby the inner and outer peripheries of the barrel and the inner and outer face of one of the heads will be properly cleaned.

It further comprehends a novel construction and arrangement of brush mechanism 20 and novel means for actuating them.

It further comprehends a novel construction and arrangement of a barrel clamping member, novel means for moving it into or out of its operative position, a novel construction and arrangement of brush mechanism, the brush of which is contained within 25 said clamping member, and novel means for taking up wear as the brushes are worn down.

30 It further comprehends a novel construction and arrangement of a brush adapted to engage the inner periphery of the barrel and the inner face of its head and novel means for effecting a radial movement of the brush 35 during its longitudinal travel so that it will follow the curved inner periphery of the barrel.

Other novel features of construction and advantage will hereinafter more fully appear 40 in the detailed description of the invention.

For the purpose of illustrating my invention, I have shown in the accompanying drawings a typical embodiment thereof which is at present preferred by me, since 45 this embodiment will be found in practice to give satisfactory and reliable results.

Figure 1 represents a top plan view of a barrel washing machine embodying my invention.

50 Figure 2 represents a side elevation of the machine.

Figure 3 represents a section on line 3—3 of Figure 1.

55 Figure 4 represents a section on line 4—4 of Figure 1.

Figure 5 represents, in sectional elevation

and on an enlarged scale, a portion of the construction seen in Figure 6.

Figure 6 represents a section on line 6—6 of Figure 1.

Similar numerals of reference indicate corresponding parts.

Referring to the drawings.

1 designates the frame of a barrel washing machine, embodying my invention. The 65 frame 1 supports a tank 2 within which is contained the solution which is to be employed to effect the cleansing of the barrel. The frame 1 is provided with the forwardly extending receiving ways or tracks 3 which 70 are preferably in the form of metallic bands which are bent intermediate their ends and each returned bend 4 is secured to a fixed portion of the frame 1. The barrels as they 75 drop onto the bent arms 5 which as illustrated are substantially L-shaped and have their upper ends fixed to a rock shaft 6 journaled in the machine frame. The rock shaft 6 has connected to it an arm 7 which 80 is connected by means of a link 8 with a bell-crank lever 9, one arm of which extends into one of the links, see Figure 3, and the other arm of which is extended upwardly to form a grasping handle as best seen in Figure 2. This lever 9 is fulcrumed at 10 on the machine frame. It will thus be seen that when the lever 9 is rocked towards the left of the position seen in Figure 2, the arms 5 which form a barrel receiving cradle will 85 raise a barrel 11 into clamping position.

12 designates a clamping head which is preferably of skeleton formation and provided with a hub which is fixed to a sleeve 13 rotatably mounted in the journals 14. 95 The sleeve 13 is provided with a sprocket wheel 15 in order that such sprocket wheel and the clamping head 12 may be continuously revolved by any desired source of power. 16 designates the other clamping 100 head which is carried by a sleeve 17 mounted in the journals 18 and provided with a clutch collar 19 with which co-operates a clutch arm 20 of a rack 21 which is slidably mounted in a guide 22. 23 designates a rack segment which is actuated by an arm 24 which with the rack segment is fixed to a rock shaft 25 on the machine frame. The arm 24 has its upwardly extending arm adapted to form a grasping handle and this arm has pivoted 110 to it the latch operating lever 26 to which is connected one end of a spring 27 the oppo-

site end of which is connected to the arm 24. The lever 26 has pivotally connected to it one end of a pawl 28 which is guided in the bracket 29 carried by the arm 24 and is 5 adapted to engage with the teeth of the stationary ratchet 30.

It will thus be seen that when the lever 24 is moved toward the right from the position seen in Figures 2 and 6, the clamping 10 head 16 will be moved rearwardly and when a barrel is in clamping position and the handle arm 24 is moved into the position seen in Figures 2 and 6, the barrel will be clamped between the clamping heads 12 and 15 16 each of which is provided with an annular groove 31 to receive the ends of a barrel.

In order to prevent the barrel from slipping during the rotation of the clamping head each clamping head is provided with 20 a desired number of studs 32 which extend into a groove 31 and are secured in place by means of the nuts 33 in threaded engagement with the shank of the studs 32.

25 *The cleaning brushes.*

I employ three different brush mechanisms one for the outer face of a head of the barrel, one for the outer periphery of the barrel and one for the inner periphery 30 of the barrel. I will first describe the brush for cleaning the outer face of the head of a barrel. This consists of a brush 34 the head of which is secured to a non-rotatable shaft 35 which extends through 35 the sleeve 17 and its rear end is pivotally connected at 35' with a lever 36 fulcrumed at 37 on the machine frame. This lever 36 has its upper portion forming a grasping handle and it has operatively connected 40 with it a cable 37' which passes over a roller 38 carried by the machine frame and is connected to a weight 39, the tendency of which is to move the shaft 35 inwardly, the extent of such movement being limited by means 45 of a set collar 40 in threaded engagement with the shaft 35 and adapted to contact with an end of the sleeve 17. By adjustment of the set collar 40 the brush 34 can be permitted to move inwardly as the brush 50 wears down.

I will next describe the brush mechanism for cleaning the outer periphery of the barrel reference being directed more particularly to Figures 1, 3 and 4.

55 41 designates a brush, the head of which is adjustably secured in a brush holder 42 by means of fastening devices 43 which pass through slots 44 in the brush holder. The brush holder 42 is adjustable on the arms 60 45 by means of fastening devices 46 which pass through slots 47 in said arms. The arms 45 are fixed to a rock shaft 48 journaled in the machine frame. The rock shaft 48 has fixed to it a lever 49 one arm 65 of which is provided with an adjustable

counterbalance 50 and the other arm of said lever 49 is connected by means of the links 51 with a foot treadle 52 which is pivotally supported at 53 on the machine frame.

70 It will thus be seen that when the foot treadle 52 is pressed downwardly the brush 41 will be moved away from the barrel, the counterweight 50 tending to maintain the brush 41 against the outer periphery of the barrel.

I will next describe the brush mechanism for cleaning the inner periphery of the barrel and the inner face of a barrel head reference being directed more particularly 80 to Figures 1, 2, 5 and 6. As best seen in

Figure 2, a sprocket wheel 54 is mounted on the machine frame and supplied with an actuating handle 55. A sprocket chain 56 passes around the sprocket wheel 54 and around the sprocket wheels 57 and 58 and a sprocket wheel 59, the latter being mounted on the shaft 60 journaled in the machine frame and carrying a pinion 61, see more particularly Figures 5 and 6. This 90 pinion 61 meshes with a rack 62 forming a part of a tubular rod 63 which is longitudinally slidable in the sleeve 13 and is keyed to a stationary bracket 64. The tubular rod 63 has fixed to its inner end a 95 brush support 65 having the key-ways 66 in which is guided the head of the brush 67 which is adapted to engage the inner face of the barrel head. A brush 68 adapted to engage the inner periphery of the barrel 100 has its head connected to the head of the brush 67 so that they are both laterally movable with respect to the longitudinal axis of the tubular rod 63. The brush 67 has connected to it near its inner end one 105 end of a cable 69 which passes through the tubular rod 63 and is connected to a weight 70. The outer end of the tubular rod 63 is provided with an antifriction cap 71 around which the cable 69 passes. The 110 head of the brush 68 has connected to it a cable 72 which passes through the tubular rod 63 around the antifriction cap 71 and its free end is provided with a hook 73 which is adapted to be secured in one of the 115 apertures 74 of a bracket 75 carried by the machine frame. The purpose of the cables 69 and 72 and their adjuncts is to cause the brushes 67 and 68 to be drawn into the clamping head 12 at the proper time, it being seen that the clamping head 12 is 120 of skeleton construction and provided with an internal chamber into which such brushes 67 and 68 can be moved, as will be best understood by reference to Figure 5. The clamping head 16 is of similar construction and being of skeleton formation and having an internal chamber into which the brush 34 can be moved, see more particularly

130 Figure 6.

The operation of my novel barrel washing machine will now be readily apparent to those skilled in the art to which this invention appertains and is as follows:—

5 The tank 2 is supplied with a cleaning liquid of any desired nature such as, for example, a caustic solution. The clamping head 12 is continuously driven by means of the sprocket wheel 15 mounted on the 10 sleeve 13 which carries the clamping head 12. The barrels to be washed are fed into the machine in any desired manner and as the barrels pass from the tracks 3 they drop onto the cradle forming arms 5. The operator 15 now rocks the handle 9 and also draws outwardly the handle 36 to move the brush 34 within the clamping head 16. The brushes 67 and 68 at this time are within the clamping head 12. When the handle 20 9 is rocked as stated the cradle forming arms 5 raise the barrel into clamping position. The operator next actuates the handle 24 thereby causing the clamping head 16 to move towards the barrel until the barrel 25 is clamped between the heads 12 and 16, the latch 28 retaining the handle 24 in its locked position with the barrel in clamped position. The operator releases the handle 36 thereby permitting the weight 39 to effect 30 the movement of the brush 34 towards the head of the barrel. The brushes are preferably formed of wire. When the operator places his foot on the treadle 52, the brush 41 will be moved away from the barrel, as 35 is apparent, and this brush 41 is retained in engagement with the periphery of the barrel by means of the weight 50. As the barrel is now revolving, the outer face of the head of the barrel will be cleaned by 40 the brush 34 and the outer periphery of the barrel will be washed and cleaned by the brush 41. The brushes 67 and 68 which are contained within the clamping heads 12 are 45 now caused to move forwardly by the operator turning the handle 55 thereby effecting the rotation of the shaft 60 and the pinion 61 which it carries and the sleeve 63 which is provided with the rack 62 engaged by the pinion 61. The forward movement of the 50 brushes 67 and 68 is thus effected and as these brushes pass from the clamping head 12 there will be a slack in the cable 72 so that the brushes 67 and 68 will have a radial movement with respect to the axis of revolution of the barrel and the brush 68 will 55 follow the contour of the inner periphery of the barrel during the longitudinal travel of such brush. As soon as the sleeve 63 reaches the forward end of its stroke, the brush 67 will be brought into engagement with the inner face of the head of the barrel so that the inner head of the barrel will be properly washed and cleaned.

When the handle 55 is actuated in a reverse direction the brushes 67 and 68 will

be moved rearwardly, the brush 68 following the contour of the inner periphery of the barrel. As the sleeve 63 reaches the end of its rearward stroke, it will be seen that the slack in the cable 72 will be taken up so 70 that the further rearward movement of the sleeve 63 will cause the cable 72 to move the brushes 67 and 68 inwardly so that they will move into the chamber of the clamping head 12. After the barrel has been washed and 75 cleaned the operator actuates the handle 24 to release the clamping head 16 and actuates the handle 36 to move the clutch 34 outwardly and the barrel drops from its clamped position onto the cradle forming 80 arms 5 and the cleaned and washed barrel is removed from the tank to a desired point of utilization.

Another barrel to be washed is now introduced into the machine and the operation 85 which has just been described is repeated. As wear occurs on the brush 34 it can be adjusted by adjustment of the set collar 40. The brush 41 can be adjusted, as is apparent, by means of the fastening devices 43 and 90 the head 42 which carries the brush 41 can be adjusted by means of fastening devices 46.

It will now be apparent that I have devised a new and useful barrel washing machine which embodies the features of advantage enumerated as desirable in the statement of the invention and the above description, and while I have, in the present instance, shown and described a preferred 100 embodiment thereof which will give in practice satisfactory and reliable results, it is to be understood that such embodiment is susceptible of modification in various particulars without departing from the spirit 105 or scope of the invention or sacrificing any of its advantages.

Having thus described my invention, what I claim as new and desire to secure by Letters Patent, is:

1. In a barrel washing machine, a tank adapted to receive a cleaning solution, a plurality of members to engage the ends of a barrel and clamp it in position, means to revolve one of said members, means to actuate the other member to clamp the barrel in position and to release it from clamping position, and brush mechanism adapted to contact with the inner and outer walls of the barrel, said brush mechanism co-operating with the inner wall of the barrel including a brush, and means to impart to it both a longitudinal and a radial movement.

2. In a barrel washing machine, a tank adapted to receive a cleaning solution, means to clamp a barrel within said tank, means to revolve said barrel clamping means, a longitudinally movable brush to engage the head of the barrel, a weight to maintain said brush in engagement with such barrel head.

a brush to engage the outer periphery of the barrel, a weight to maintain said second brush in engagement with the outer periphery of the barrel, and brush mechanism capable of both longitudinal and radial movement to clean the inner periphery of the barrel and the inner face of the barrel head.

3. In a barrel washing machine, a tank adapted to receive a cleaning solution, means to clamp a barrel within said tank, means to revolve said barrel clamping means, a manually controlled brush to engage the outer face of the head of the barrel, a brush to engage the inner face of the head of the barrel, and means to move said second brush into and out of engagement with the inner face of the head of a barrel, and to cause said brush to follow the contour of the inner periphery of said barrel.

4. In a barrel washing machine, a tank to receive a cleaning solution, means including clamping heads to clamp a barrel within said tank, means to revolve said clamping heads, a longitudinally movable sleeve, a brush movably carried thereby, a counterbalance for said brush, a cable connected with said brush and passing through said sleeve and having its other end secured to a fixed point whereby on the inward movement of the sleeve the brush will follow the inner periphery of the barrel and on the outward movement of said sleeve the brush will be moved

into one of said barrel clamping heads, and means to effect longitudinal movement of said sleeve.

5. In a barrel washing machine, a tank to receive the cleaning solution, a cradle to raise a barrel into clamping position, means to clamp the barrel, means to revolve the clamping means and thereby the barrel, a rock shaft, a brush mechanism adjustably carried by said rock shaft and adapted to engage the periphery of the barrel, a counterbalance for said rock shaft, means to actuate said rock shaft to vary the relation of the brush mechanism with respect to the barrel, and brush mechanism to engage the inner periphery of the barrel.

6. In a barrel washing machine, a tank to receive the cleaning solution, means to clamp a barrel in said tank, means to revolve the clamping means and thereby the barrel, a brush to engage the head of the barrel, means to move said brush to and from said head, a sleeve on which a portion of said barrel clamping means is mounted, a rack operatively connected with said sleeve to move it, and a manually controlled rack segment co-operating with said rack.

MICHAEL P. WEIMAR.
